SHOE SUPPORTING JACK

Robert H. Lawson, Beverly, Mass., assignor to
 United Shoe Machinery Corporation, Borough
 of Flemington, N. J., a corporation of New
 Jersey

Application May 12, 1939, Serial No. 273,234

8 Claims. (Cl. 12—127)

The present invention relates to shoe supporting jacks for use in machines used in the manufacture of shoes, and is intended primarily as an improvement in the shoe supporting jack disclosed in applicant's prior Patent No. 1,999,298 dated April 30, 1935.

The objects of the invention are to simplify and improve certain of the mechanisms disclosed in said patent, and more particularly the mechanism for releasing the shoe clamping mechanism, when a last is placed upon a jack, the mechanism for resetting the shoe clamping mechanism and the devices for locking the swinging cradle on which the shoe is supported from swinging movements except while the machine in which the jack is used is in operation.

With the above objects in view, a feature of the invention is embodied in a construction in which the pin which is depressed by the act of placing a last on the heel support of the jack to release the shoe clamping mechanism is arranged to act directly on the actuating pawl of the jack resetting mechanism. In connection with this feature, means are provided for imparting an additional movement to the pawl as soon as it is disengaged from the heel support carrying slide so as to prevent the pin from being engaged by the pawl during the movement of the heel support slide towards the toe support in clamping the shoe. Also in connection with this feature means are provided for holding the pawl out of contact with the pin or with the slide during the return movement of the pawl while the machine is in operation and also for moving the pawl into a position to engage the slide at the start of the advancing movement of the pawl.

Another feature of the present invention is embodied in a construction comprising a locking mechanism connected to the slide carrying the heel support and arranged to be actuated by the pawl during its advancing movement to center the swinging cradle and lock the cradle from swinging movements.

Other features of the invention are embodied in certain novel constructions and arrangements of parts hereinafter described and claimed, the advantages of which will be obvious to those skilled in the art from the following description, taken in connection with the accompanying drawings in which Fig. 1 is a view in side elevation, partly in section, of the upper portion of a shoe supporting jack embodying the present invention; Fig. 2 is a sectional plan view, taken on the line 2—2 of Fig. 1; Fig. 3 is a detail vertical sectional view, taken on the line 3—3 of Fig. 1;

Fig. 4 is a detail plan view illustrating a frictional connection between the actuating pawl bar of the clamp resetting mechanism and a supporting lever; Fig. 5 is a view similar to Fig. 1, but with the shoe illustrated in clamped position and with the pawl bar at the limit of its retracting movement; Fig. 6 is a view similar to Fig. 5, but with the pawl bar in the position it assumes just prior to engaging the shoulder on the slide; and Fig. 7 is a vertical sectional view, taken on the line 7—7 of Fig. 6.

The shoe supporting jack illustrated in the drawings comprises a jack frame 8, a cradle 10 pivotally mounted in the jack frame to swing about an axis extending close to the bottom of a supported shoe lengthwise of the shoe, a heel supporting last pin 12 projecting from a slide 14 mounted in the cradle 10, a toe support for the shoe comprising toe supporting grips 16, and a toe gage 18, said toe grips and toe gage being also mounted on the cradle 10. When the parts are in position to receive the shoe, as illustrated in Figure 1, the heel support 12 is held against movement towards the toe support by means of a lug 20 projecting from a pawl bar 22 and engaging a shoulder on the slide 14. A spring 24 connected at one end to the cradle 10 and at the other end to the slide 14 moves the slide with the heel supporting last pin 12 towards the toe rest to clamp the shoe on the jack, as illustrated in Fig. 5, as soon as the pawl is moved out of engagement with the shoulder on the slide. To release the slide when a shoe is placed on the jack, a spring supported plunger 26 is mounted in the last pin 12 and is arranged, when depressed by the placing of a shoe on the jack, to move the pawl 22 out of engagement with the shoulder on the slide 14.

As so far described, the construction and arrangement of the parts is substantially the same as in the jack disclosed in applicant's prior Patent No. 1,999,298 above referred to, and in applicant's pending application Serial No. 231,750 filed September 26, 1938. In the present construction, however, the spring supported plunger 26, instead of acting on the pawl through an intervening lever, is arranged to act directly on the pawl 22. At its forward end, the pawl is pivotally mounted upon an actuating lever 28 which is supported and actuated as in the construction disclosed in applicant's pending application, being mounted upon supporting links 30 and 32, and connected by a link 34 to a crank 36 on a pulley 38 mounted in the jack frame. The rear end of the pawl 22 is supported, as hereinafter de-

scribed, and in order to prevent the lug 20 of the pawl from being engaged by the lower end of the plunger 26 during the movement of the slide towards the toe rest, after being released by the 5 downward movement of the plunger, a spring pressed curved lever 40 is provided mounted in the jack frame and arranged to engage at its upper end with an inclined surface at the rear end of the pawl 22 and impart a further downward movement to the pawl as soon as it is moved by the plunger 26 sufficiently to disengage the lug 20 from the shoulder on the slide 14.

The means for supporting the pawl 22 at its rear end is constructed and arranged to cause the pawl to be retained in its lowest position during the return movement of the pawl and to be moved upwardly into a position to engage the shoulder on the slide 14 as soon as the pawl begins its advancing movement to move the 20 slide 14 against the tension of the spring 24 and unclamp the shoe. The means for thus supporting the pawl 22 comprises a supporting lever 42 pivotally mounted on the jack frame and provided with a vertical portion extending downwardly between limiting stops 44 and 45 and with a horizontal portion having a frictional sliding engagement with the pawl 22. As best shown in Figure 4, the connection between the horizontal arm of the lever 42 and the pawl 22 comprises 30 a pivot pin 46 extending through friction plates 48 on opposite sides of the pawl and through a longitudinal slot 50 in the pawl. A frictional engagement of the plates 48 with the pawl 22 is secured by springs 52 mounted on opposite 35 ends of a pin 54 extending through the plates 48 and through the slot 50, said spring being located between a plate 48 and a nut 56 on the outer end of the pin 54. An upwardly extending forked portion of the lever 42 acts as a lateral 40 guide for the pawl.

Briefly stated, the operation of the mechanism above described is as follows. When the machine in which the jack is used is at rest with the jack in position to receive a shoe, the mechanism of the jack is in the position illustrated in Figure 1. Upon placing a shoe on the jack, the plunger 26 is depressed, thereby moving the pawl 22 downwardly to disengage the lug 20 on the pawl from the slide 14, and bringing it into a 50 position so that the spring pressed lever 40 continues the downward movement of the pawl to carry the lug 20 out of the path of the lower end of the plunger 26 as the slide 14 moves towards the toe rest into the position indicated in 55 Figure 5. During the operation on the shoe, the pulley 33 is rotated in a clockwise direction by mechanism which may be the same as that disclosed in applicant's pending application, and during this clockwise rotation, the pawl 22 is 60 moved to the right. During the movement of the pawl 22 to the right, the frictional engagement between the horizontal arm of the lever 42 and the pawl holds the lever 42 in a position in which the downwardly extending portion of the lever 65 is in engagement with the stop 44, and thereby the pawl 22 is held in its depressed position and the lug 20 of the pawl passes beneath the lower end of the plunger 26 and beyond the shoulder on the slide 14, as indicated in Figure 5. At the 70 conclusion of the operation on the shoe, the pulley 33 may be rotated in the opposite direction as in the machine of applicant's pending application, and during this rotation the pawl 22 is moved towards the left. During the first part 75 of this movement, the lever 42 is swung about its

5 pivot, as indicated in Figure 6, by reason of the frictional connection between the horizontal portion of the lever and the pawl. Thereby the pawl is raised into a position where continued movement of the pawl to the left will cause the lug on the pawl to engage the shoulder on the heel support carrying slide 14. Continued movement of the pawl to the left brings the heel support carrying slide 14 to the position indicated in Figure 1, and thereby unclamps the shoe on the 10 jack.

The improved means illustrated in the drawings for locking the cradle 10 from swinging movements except while the machine in which the jack is used is in operation comprises a locking device mounted on the slide carrying the heel support and arranged to be engaged by the pawl which actuates the slide to unclamp the shoe. This locking device comprises a V-shaped 15 guide indicated at 58 rigidly secured to the underside of the slide 14 adjacent the plunger 26. This V-shaped guide in the construction illustrated provides the shoulder on the slide 14 which cooperates with the projecting lug 20 of the pawl 22. As the projection 20 of the pawl 20 moves into engagement with the guide 58, the pressure of the guide against the lug, due to the 25 action of the spring 24, centers the guide and with it the slide 14 and the cradle 10 in which the slide is mounted, and effectively prevents 30 any swinging movement of the cradle on the jack frame so long as the lug 20 and guide 58 remain in engagement.

The nature and scope of the invention having 35 been indicated, and an embodiment of the several features of the invention having been specifically described, what is claimed is:

1. In a machine for use in the manufacture of shoes, a shoe supporting jack comprising a jack frame, a shoe supporting cradle mounted 40 in the jack frame to swing about an axis extending longitudinally of a shoe on the cradle in proximity to the plane of the shoe sole, shoe clamping means mounted on the cradle comprising a toe rest, a heel support, a slide on which the heel support is mounted, a spring tending to move the slide towards the toe rest to clamp the shoe, a pawl mounted on the jack frame arranged to engage a shoulder on the slide, means for actuating the pawl to move the slide away from 45 the toe rest, and a locking device on the slide 50 arranged to be engaged by the pawl to lock the cradle from swinging movement.

2. In a machine for use in the manufacture of shoes, a shoe supporting jack, comprising a 55 jack frame, a shoe supporting cradle mounted in the jack frame to swing about an axis extending longitudinally of a shoe on the cradle in proximity to the plane of the shoe sole, sole clamping means mounted on the cradle comprising a toe rest, a heel support, a slide on which the heel support is mounted, a spring tending to move the slide towards the toe rest to clamp the shoe, a pawl mounted on the jack frame arranged to engage a shoulder on the slide, means 60 for actuating the pawl to move the slide away from the toe rest, and a V-shaped guide on the slide arranged to be engaged by the pawl to center the cradle and lock it from swinging movement.

3. In a machine for use in the manufacture of 70 shoes a shoe supporting jack, shoe clamping means mounted on the jack comprising a toe rest, a heel support, a slide on which the heel support is mounted, a spring tending to move the slide 75

- towards the toe rest to clamp the shoe, a pawl mounted on the jack frame arranged to engage a shoulder on the slide, means for actuating the pawl to move the slide away from the toe rest, 5 a pin on the slide arranged to engage the pawl and to be actuated by a last placed on the heel support to disengage the pawl from said shoulder, and means for moving the pawl when so disengaged out of the path traversed by the pin during 10 the shoe clamping movement of the slide.
4. In a machine for use in the manufacture of shoes, a shoe supporting jack, shoe clamping means mounted on the jack comprising a toe rest, a heel support, a slide on which the heel support is mounted, a spring tending to move the slide towards the toe rest to clamp the shoe, a pawl bar provided with a shoulder arranged to engage a shoulder on the slide, a pin on the slide arranged to engage the pawl bar and to be actuated by a 15 last placed on the heel support to disengage the pawl bar from the slide, means for reciprocating the pawl bar, a supporting lever arranged to move the bar towards and away from a position to engage the shoulder on the slide, a frictional sliding 20 connection between the supporting lever and bar, and stops to limit the movement of the supporting lever.
5. In a machine for use in the manufacture of shoes, a shoe supporting jack, shoe clamping means mounted on the jack comprising a toe rest, a heel support, a slide on which the heel support is mounted, a spring tending to move the slide towards the toe rest to clamp the shoe, a pawl bar provided with a shoulder arranged to 25 engage a shoulder on the slide, a pin on the slide arranged to engage the pawl bar and to be actuated by a last placed on the heel support to disengage the pawl bar from the slide, means for reciprocating the pawl bar arranged to impart an advancing movement to the bar to move the slide away from the toe rest and a return movement, and means for holding the bar out 30 of contact with the pin during its return movement.
6. In a machine for use in the manufacture of shoes, a shoe supporting jack, shoe clamping means mounted on the jack comprising a toe rest, a heel support, a slide on which the heel support is mounted, a spring tending to move the slide towards the toe rest to clamp the shoe, a pawl bar provided with a shoulder arranged to 35 engage a shoulder on the slide, means for actuating the pawl to move the slide away from the toe rest, a pin on the slide arranged to engage the pawl and to be actuated by a last placed on the heel support to disengage the pawl from said shoulder, and a spring pressed lever arranged to move the pawl when so disengaged out of the path traversed by the pin during the shoe clamping 40 movement of the slide.
7. In a machine for use in the manufacture of shoes, a shoe supporting jack, shoe clamping means mounted on the jack comprising a toe rest, a heel support, a slide on which the heel support is mounted, a spring tending to move the slide towards the toe rest to clamp the shoe, a pawl bar provided with a shoulder arranged to engage a shoulder on the slide, a pin on the slide arranged to engage the pawl bar and to be actuated by a last placed on the heel support to 45 disengage the pawl bar from the slide, means for reciprocating the pawl bar, arranged to impart an advancing movement to the bar to move the slide away from the toe rest and a return movement, and means actuated by the reciprocating movements of the bar for moving the bar towards and away from a position to engage the shoulder on the slide.

ROBERT H. LAWSON. 50

CERTIFICATE OF CORRECTION.

Patent No. 2,194,360.

March 19, 1940.

ROBERT H. LAWSON.

It is hereby certified that error appears in the printed specification of the above numbered patent requiring correction as follows: Page 2, second column, line 59, claim 2, for "sole" second occurrence, read --shoe--; and that the said Letters Patent should be read with this correction there-in that the same may conform to the record of the case in the Patent Office.

Signed and sealed this 25th day of June, A. D. 1940.

Henry Van Arsdale,

Acting Commissioner of Patents.
